HANDLE OPERATED LATCH FOR
RECEPTACLES

Wallace H. Cadwell, New Carlisle, Ohio

Application May 26, 1945, Serial No. 596,011

3 Claims. (Cl. 220—56)

1

This invention relates to latch mechanisms, and particularly to latch mechanisms for locking hinged cover members upon a body member, such as a lid upon a box.

An object of the invention is to provide a latch mechanism that is operably connected with a handle for opening the lid of a container so that immediately upon picking up the handle to carry the container, the lid of the container will automatically be locked in closed position.

Another object of the invention is to provide a latch mechanism in accordance with the foregoing object wherein the latch mechanism has one position in which it is rendered ineffective for locking a lid upon a container, but immediately upon grasping the handle of the container, the latch mechanism is rendered active and locks the lid of the container in closed position. Another object of the invention is to provide a container having a lid thereon that is provided with a latch mechanism carried on the lid of the container and is actuated by a carrying handle supported upon the lid of the container so that movement of the carrying handle into position for carrying the container automatically locks the latch mechanism for holding the lid of the container in closed position.

Another object of the invention is to provide an apparatus in accordance with the foregoing object wherein the latch mechanism has an inoperative position to permit the lid of the container to be opened and closed without actuating the latch mechanism, but which is immediately moved out of the inactive position to an active position for locking the lid of the container immediately upon movement of the carrying handle for the container into a carrying position.

Still another object of the invention is to provide an automatically locking latch mechanism for a container that is operated by a carrying handle on the container so that the latch mechanism will be locked immediately upon any action tending to lift the container by the carrying handle thereof, and thereby prevent the contents of the container from spilling therefrom.

Further objects and advantages will become apparent from the drawings and the following description.

In the drawings:

Figure 1 is a perspective elevational view of a container having the latch mechanism of this invention applied thereon, a part of the container being broken away and in cross-section to show the latch mechanism, and which also shows the latch mechanism in its active locking position.

Figure 2 is a perspective elevational view of a portion of the container and of the latch mechanism illustrated in Figure 1 but showing the latch mechanism in an inactive position.

Figure 3 is a transverse cross-sectional view of

2

the container showing the latch mechanism mounted upon the lid of the container.

Figure 4 is a horizontal cross-sectional view taken along line 4—4 of Figure 1.

5 The latch mechanism of this invention is illustrated as being applied upon a container that consists of a lower pan-shaped portion 10 and a cover or lid portion 11 that is hinged to the lower portion 10 by means of one or more hinges 12. The front wall 13 of the lower pan-shaped portion 10 is provided with a latch-receiving member 14 that has a hole 15 therein which cooperates with the latch hereinafter disclosed and described.

10 15 The cover portion 11 of the container is provided with a carrying handle 16 that is rotatably carried by a bracket member 17 positioned at each end of the housing 18 that covers the opening 19 provided in the top cover 11. The carrying handle 16 is thus rotatably supported in the bracket members 17 so that the handle can be disposed in a horizontal position as illustrated in Figures 2 and 3 or in a vertical position as illustrated in Figure 1. The carrying handle 16 is provided with an actuating member 20 that 20 extends from the handle 16 and is normal thereto. This actuating member 20 operates the latch mechanism for locking and unlocking the same.

25 30 The latch member consists of a rod 21 that is rotatably carried in the brackets 22 secured to the underside of the lid 11. The rod 21 is bent at one end thereof to provide a downwardly extending portion 23 that is at right angles to the rod portion 21. The lower end of the rod portion 23 is bent at right angles to the portion 23 to form a locking or latch member 24 that is adapted to enter the hole 15 in the latch-receiving member 14 and enters a hole 25 provided in the latch-receiving member 26 that is mounted along the 35 lower edge of the front wall 27 of the cover 11. It will therefore be seen that axial rotation of the rod portion 21 in the brackets 22 will cause the lock or latch portion 24 to enter the latch-receiving members 14 and 26, as illustrated in 40 Figure 4, or be removed therefrom, as illustrated in Figure 2.

45 50 The latch rod 21 carries an extending arm 30 that is suitably secured to the rod 21, and is substantially radial thereto. This extending arm 30 is engaged by one end of a torsion spring 31 that has the opposite end thereof engaging the under side of the top wall of the cover 11, whereby the torsion spring 31 normally urges 55 the arm 30 in a clockwise direction of rotation, as viewed in Figure 1.

The torsion spring 31 holds the arm 30 against the actuating member 20 so that the position of the actuating member 20 determines whether 60 the latch portion 24 is in engagement with or

out of engagement with the latch or lock receiving members 14 and 26.

With the carrying handle 16 in horizontal position, as illustrated in Figures 2 and 3, the actuating member 20 will be in an upward position so that the torsion spring 31 will hold the arm 30 against the actuating member 20 and the lock portion 24 of the latch rod 21 will be disengaged from the holes 15 and 25 in the latch-receiving members 14 and 26, respectively, thereby retaining the lock portion 24 in an unlocked position so that the lid 11 of the container can be opened and closed without causing actuation of the latching device. A suitable handle 35 is provided for raising and lowering the lid 11 when the carrying handle 16 is in horizontal or inactive position.

When the lid 11 of the container is closed upon the lower portion 13 and a person wishes to pick up the container by the carrying handle 16, the latch mechanism will be automatically actuated to lock the lid 11 to the lower portion 13 of the container. This is accomplished because when the actuating handle is grasped by a person picking up the container by the carrying handle thereof, the carrying handle will be rotated axially within the bracket member 17 thereby causing the actuator 20 to move the arm 30 downwardly in a counter-clockwise direction, as viewed in Figure 1. This movement of the arm 30 rotates the rod 21 in a counter-clockwise direction to thereby cause the latch or lock portion 24 of the latch rod to engage the holes 15 and 25 in the latch-receiving members 14 and 26, respectively, and thereby lock the lid 11 to the lower portion 13 of the container before the weight of the container is fully carried by the carrying handle 16.

It will therefore be seen that a person wishing to carry the container having the latch of this invention thereon cannot forget to lock the lid to the main body of the container and thus spill the contents thereof because the carrying handle 16 automatically locks the lid to the main body portion of the container before the weight of the container is supported upon the carrying handle. Also, it will be seen that when the carrying handle 16 is placed in a horizontal position, as illustrated in Figures 2 and 3, the lid of the container can be raised and lowered without causing actuation of the latching or locking mechanism.

While the apparatus disclosed and described herein constitutes a preferred form of the invention, yet it will be understood that the device is capable of mechanical alteration without departing from the spirit of the invention, and that all modifications that fall within the scope of the appended claims are intended to be included herein.

Having thus fully described my invention, what I claim as new and desire to secure by Letters Patent is:

1. In combination, a container, a lid hinged on said container, locking means including a shaft, bearings on said lid for rotatively supporting said locking means on said lid, a lock-receiving member carried on said container for receiving said locking means, spring means engaging said locking means normally urging the same out of locking engagement with said lock-receiving member, handle means including a shaft, bearings on said lid for supporting the shaft of

handle means for rotation in a plane at substantially right angles to the plane of rotation of said locking means, and actuating means extending between the shaft on the handle means and the shaft on the locking means for rotating said locking means into locking engagement with said lock-receiving member upon rotation of said handle means into carrying position.

2. In combination, a container, a lid hinged on said container, locking means including a shaft, bearings on said lid for rotatively supporting said locking means on said lid, a lock-receiving member carried on said container for receiving said locking means, spring means engaging said locking means normally urging the same out of locking engagement with said lock-receiving member, handle means including a shaft, bearings on said lid for supporting the shaft of said handle means for rotation in a plane at substantially right angles to the plane of rotation of said locking means, and actuating means extending between the shaft on the handle means and the shaft on the locking means for rotating said locking means into locking engagement with said lock-receiving member upon rotation of said handle means into carrying position, said actuating means including an actuating member extending from the shaft on the handle means and an arm mounted on the shaft on the locking means, said spring holding said arm against said actuating member.

3. In combination, a container, a lid hinged on said container, locking means including a shaft, bearings on said lid for rotatively supporting said locking means on said lid, a lock-receiving member carried on said container for receiving said locking means, spring means engaging said locking means normally urging the same out of locking engagement with said lock-receiving member, handle means including a shaft, bearings on said lid for supporting the shaft of said handle means for rotation in a plane at substantially right angles to the plane of rotation of said locking means, and actuating means extending between the shaft on the handle means and the shaft on the locking means for rotating said locking means into locking engagement with said lock-receiving member upon rotation of said handle means into carrying position, said actuating means comprising a cam member secured to the shaft of the handle means and an actuating member secured to the shaft of the locking means and bearing and actuating by said spring means into engagement with said cam member.
